ELECTRON DISCHARGE DEVICE EMPLOYING CAVITY RESONATOR APPARATUS

Charles A. Rosenerans, Haddonfield, N. J., assignor to Radio Corporation of America, a corporation of Delaware

Application February 17, 1945, Serial No. 578,467

5 Claims. (Cl. 315—39)

1

My invention relates to electron discharge devices and associated circuits useful at ultra high frequencies and more particularly to such devices utilizing cavity resonators.

It is an object of my invention to provide an electron discharge device and associated circuit of the cavity resonator type in which the circuit is readily tunable and in which feedback between output and input can be easily controlled so that the apparatus may be used as an oscillator or as an amplifier.

It is another object of my invention to provide such a device in which the feedback controlling means is of novel and simple design.

The novel features which I believe to be characteristic of my invention are set forth with particularity in the appended claims, but the invention itself will best be understood by reference to the following description taken in connection with the accompanying drawing in which Figure 1 is a longitudinal section showing an electron discharge device and associated cavity resonator made according to my invention, Figure 2 is a plan view of Figure 1, Figure 3 is a section taken along the line 3—3 of Figure 1, Figure 4 is a section taken along the line 4—4 of Figure 1, and Figure 5 is an equivalent circuit diagram of the apparatus shown in Figures 1 to 4, inclusive.

According to my invention I use an electron discharge device having at one end 10, a cathode (not shown) and at the other end 11 an anode with an intermediate grid having a grid contact ring 12, the electrodes being spaced in insulating relationship by means of the envelope of the tube.

In accordance with my invention I employ cavity resonator circuits. These may be formed by utilizing a box-shaped hollow conducting member 13 provided with an intermediate partition 14, the top and bottom of the member 13 and the partition being provided with apertures through which the electron discharge device may extend. An input cavity resonator 15 is thus provided between the cathode and grid, and output cavity resonator 16 between the grid and the anode, each of these being tuned by plunger members 18 and 19 in the form of slides which vary the size of the internal cavity coupled between the various electrodes. In the arrangement shown, the anode 11 is capacity coupled through insulating ring 11' to the top of the hollow conducting member 13 and the cathode capacity coupled through the insulating ring 10', the grid being directly connected to the partition 14 by means of spring contact members 17.

At one end of the resonator, oppositely dis-

2

posed to the tuning elements 18 and 19, each of the resonators is provided with a longitudinally extending aperture such as 22 in the anode-grid cavity and the aperture 23 in the cathode-grid cavity to permit feedback and proper tuning. The partition 14 is hollow and comprises two sections 20 and 21 spaced from each other for purposes to be described.

In accordance with my invention, telescoped over one end of the hollow conducting member 13 is the conducting sleeve 24 provided with an intermediate partition 25 spaced at one end from the walls of the sleeve to provide an opening 26. Thus the interior of the output resonator 16 is coupled through the aperture 22 to what amounts to a transmission line formed by the conducting sleeve, radio frequency energy passing through aperture 22, around partition 25, back through the aperture 23, into the grid-cathode space. The phase relationship of the energy fed back is determined by the distance travelled by the energy from aperture 22 to aperture 23. This distance can be varied by varying the amount the sleeve is telescoped over the hollow resonator member 13. The partition 25 may in some cases be removed.

The equivalent circuit diagram is shown in Figure 5. Like numbers indicate like parts as in other figures.

While I have indicated the preferred embodiments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

1. An electron discharge device having a cathode, grid and anode, and a resonator device for said electron discharge device including a hollow conducting elongated member having one side coupled to said cathode and the other side coupled to said anode, and a partition extending through said hollow conducting member longitudinally thereof whereby two resonant chambers are provided, and electrical connections between said grid and said partition, said hollow conducting member having adjacent apertures opening into said chambers, and hollow conducting means telescoped with said hollow conducting member and provided with a partition, said partition pro-

viding an opening between opposite sides of said hollow conducting means.

2. An electron discharge device having a cathode, grid and anode, a resonator device for said electron discharge device and including a hollow flat elongated conducting member of rectangular transverse section, one side of said hollow conducting member being coupled to said cathode and the other side to said anode, a conducting partition extending longitudinally of said hollow conducting member and through which said electron discharge device extends and electrically connected to said grid and providing two resonant chambers, one end of said hollow conducting member having apertures opening into each of said chambers, said partition having a portion including spaced walls and a hollow conducting means telescoped over said hollow conducting member over the portion provided with said apertures, said telescoped conducting means having a partition extending theracross for dividing said conducting means into two compartments, said last partition providing a passageway between said compartments, said last partition being received between the walls of said partition within said conducting member, said conducting means being movable with respect to said hollow conducting member for controlling feedback from one of said chambers to the other of said chambers.

3. An electron discharge device having a cathode, grid and anode, a resonator device for said electron discharge device and including a hollow conducting member, one side of said hollow conducting member being coupled to said cathode and the other side to said anode, a conducting partition extending longitudinally of said hollow conducting member and through which said electron discharge device extends and electrically connected to said grid, said partition providing two chambers, one end of said hollow conducting member having apertures opening into each of said chambers, a hollow conducting means telescoped over said hollow conducting member over the end provided with said apertures, said telescoped conducting means having a partition extending theracross for dividing said conducting means into two compartments, said last partition providing a passageway between said compartments, said hollow conducting means being movable with respect to said hollow conducting member for controlling feedback from one of said chambers to the other of said chambers, and means within said chambers for tuning said chambers.

4. An electron discharge device having a cathode, grid and anode, a resonator device for said electron discharge device and including a hollow flat elongated conducting member of rectangular transverse section, one side of said hollow conducting member being coupled to said cathode and

the other side to said anode, a conducting partition extending longitudinally of said hollow conducting member and through which said electron discharge device extends and electrically connected to said grid and dividing said hollow conducting member into two chambers, one end of said hollow conducting member having apertures opening into each of said chambers, said partition having a portion including spaced walls and a hollow conducting means telescoped over said hollow conducting member over the portion provided with said apertures, said telescoped conducting means having a partition extending theracross for dividing said member into two compartments, said last partition defining a passageway between said compartments, said last partition being received between the walls of said partition within said hollow conducting member, said hollow conducting means being movable with respect to said hollow conducting member for controlling feedback from one of said chambers to the other of said chambers, and means within each of said chambers for separately tuning said chambers.

5. An electron discharge device having a cathode, grid and anode, a resonator device for said electron discharge device and including a hollow conducting member, one side of said hollow conducting member being coupled to said cathode and the other side to said anode, a conducting partition extending longitudinally of said hollow conducting member and through which said electron discharge device extends and electrically connected to said grid and providing two chambers, one end of said hollow conducting member having restricted apertures opening into each of said chambers, an elongated hollow conducting means telescoped over said hollow conducting member over the portion provided with said apertures, said telescoped hollow conducting means having a partition secured thereto, and being movable with respect to said hollow conducting member for controlling energy feedback from one of said chambers to the other of said chambers, the phase relationship of the energy fed back being determined by the distance traveled by said energy between said restricted apertures.
